Primary Examiner — Stacia A Cadmus(74) *Attorney, Agent, or Firm* — Greenberg Traurig, LLP(57) **CLAIM**

The ornamental design for a wheel flange, as shown and described.

DESCRIPTION

FIG. 1 is a front perspective view of a wheel flange showing our new design;

FIG. 2 is a rear perspective view thereof;

FIG. 3 is a front view thereof;

FIG. 4 is a rear view thereof;

FIG. 5 is a side view thereof;

FIG. 6 is a top view thereof;

FIG. 7 is a bottom view thereof;

FIG. 8 is a cross-sectional view thereof taken along line 8-8 in FIG. 5;

FIG. 9 is a cross-sectional view thereof taken along line 9-9 in FIG. 6;

FIG. 10 is an enlarged view of a portion of the wheel flange indicated by area 10 in FIG. 1; and,

FIG. 11 is an enlarged view of a portion of the wheel flange indicated by area 11 in FIG. 2.

In the drawings the broken lines depict environmental subject matter and form no part of the claimed design.

1 Claim, 11 Drawing Sheets(56)
